UNITED STATES PATENT OFFICE.

HORACE L. RENNE, OF HAMMOND, INDIANA.

CAR-COUPLING.

SPECIFICATION forming part of Letters Patent No. 536,894, dated April 2, 1895.

Application filed May 20, 1893. Renewed September 18, 1894. Serial No. 523,348. (No model.)

To all whom it may concern:

Be it known that I, HORACE L. RENNE, a citizen of the United States, and a resident of Hammond, in the county of Cass and State 5 of Indiana, have invented certain new and useful Improvements in Car-Couplings; and I do hereby declare that the following is a full, clear, and exact description of the invention, which will enable others skilled in the art to 10 which it appertains to make and use the same, reference being had to the accompanying drawings, which form a part of this specification, and in which—

Figure 1 is a perspective view of the front 15 end of a box car equipped with my improved coupling. Fig. 2 is a side elevation showing the front ends of two cars, equipped with my improved coupling, coming together for coupling; one of the "buffers" on the car to the 20 right having been broken away, the better to illustrate the construction of the coupling *per se*. Fig. 3 is a front elevation of a box car equipped with my improved coupling. Fig. 25 4 is a detail view in perspective, of the drawhead and drawbar (which form essential parts of my improved coupling) removed from the car. Fig. 5 is a perspective detail view of my link or coupling device. Fig. 6 is a similar view of a coupling device of a somewhat 30 modified construction, to facilitate its use with cars provided with the ordinary "pin-and-link" coupling. Fig. 7 is a perspective detail view of the bifurcated, link-guide; and Fig. 8 is a detail view of the catch or locking- 35 device for holding the side coupling-lever in its "down" position, to lift and maintain the link out of engagement with the drawhead.

Like letters of reference denote corresponding parts in all figures. 40 This invention relates to automatic car 45 couplings of the particular type employing a link or connecting device in the nature of a short bar having a crosshead or T at each end, adapted to engage and interlock with drawheads of peculiar construction; and my improvement consists in the novel and specific construction and combination of parts of a coupler of that class as will be hereinafter more fully described and claimed; the object 50 of my said improvement being to produce an automatic coupler of sufficient strength and durability to adapt it for use on freight cars

as well as on passenger coaches, and yet so inexpensive that it may be used profitably on coal and freight cars, which are still for the 55 greater part (especially on Western roads) equipped with the old-fashioned, dangerous and obsolete "pin-and-link" couplings.

Referring to the drawings, the letters A A denote the front ends of two box cars 60 supposed to stand on the same track and ready to be coupled together.

As the coupling devices are the same on both cars, one being an exact duplication of the other, it will be necessary only to de- 65 scribe the devices appertaining to one of the cars, and these are: the drawhead B and drawbar C, preferably made in one piece, and the latter inserted through a coiled spring, D, as usual, placed beneath the floor of the 70 platform and car, and between the side-sills of the car-body, in the usual well-known way. The projecting front end of the drawhead B is bifurcated so as to form a recess E, the sides of which are formed by stout hooks, 75 F F, the points f f of which are bent rearwardly, so as to overlap the T head of the link when the latter is in operative or "coupled" position. At this point it may be as well to describe the link or coupling device proper 80 which, in its usual form as illustrated in Fig. 5, is really not a link at all, in the usual acceptance of the term, but a short bar G, the middle part of which, on both sides, is grooved or recessed transversely, as shown at g, to receive two short arms, H H, connected rigidly 85 to each other and to the bar G by a transverse bolt h, and connected at the top by a bolt or crosshead i, thus forming an oblong link, at right angles to and connected rigidly 90 with, bar G, for the attachment of the chain I by which the link is operated.

At each end of bar G is a short crosshead J, of such length that it will span the opening or recess E in the drawhead, opposite ends 95 of the crossheads being grasped (when the device is in its operative or coupled position) by the rearwardly curved coupling hooks E F. The bar is suspended by the chain I from an arm K, which projects at right angles 100 from a rod, L, working in staples or bearings, l l, fastened in the front side of the car, in such a manner that this rod L not only may be turned in its bearings l l, but it can be slid

sidewise by pushing or pulling upon its lever handle L'. To the outer end of arm K is also attached a chain, I', which extends up to the roof of the car where it may be fastened in a hooked standard M. When chain I' is so fastened, it will sustain arm K in the position shown in Fig. 1, lifting the coupling-bar clear off the drawhead, but in alignment therewith.

When it is desired to throw the coupling bar entirely out of the way on one car, so as to permit its drawhead to engage the coupling-bar appertaining to the car opposite (each car being provided, at each coupling, with a coupling-bar or link, but only one of these being in use between two cars), the rod L is turned by its handle L' so as to bring arm K up against the front side of the car, thus raising the coupling-bar clear off the buffers; and by now pushing rod L endwise in its bearings, the coupling-bar, suspended by chain I from arm K, will be carried with said arm sidewise, out of the way of the drawhead, in which position (shown in dotted lines in Fig. 3) it may be maintained by pushing the lower end of lever L' into the keeper N, which consists of a curved leaf-spring located on one side of the buffer and adapted to grasp and engage, by friction, the lower end of lever handle. (See Fig. 8.) By this operation, the coupling-bar is raised and carried to one side, so as to leave the entrance to the drawhead perfectly clear and unobstructed, so that the coupling-bar appertaining to the opposite car may enter and effect the coupling.

When it is desired to return the coupling-bar to its normal position in the drawhead, lever L' is released from its lock or keeper N, rod L is pulled back in its bearings l l till the coupling-bar comes just above the drawhead, in the position shown in dotted lines in Fig. 1; and by now grasping the chain I', secured to standard M, the coupling bar G can be lowered down into the hooked drawhead. It is guided into this position by the converging and depending arms o of the link-guide O; the crosshead J of the coupling-bar entering from above the space between the parallel sides O of the guide, as illustrated in the detail view Fig. 7; and, as it is lowered into the

seat formed by the curved hooks E F, the depending and converging front sides o o of the guide will prevent the crosshead J from swinging out, so that it may be readily dropped into its seat.

In order to couple the cars, the link or coupling-bar is held, by arm K and chains I and I', in the raised position, in alignment with the drawhead, shown in Fig. 1, and when the cars come together, it is lowered, through the guides O O of both cars, until its T heads engage the hooked drawheads of both cars below the guides. To again uncouple the cars, all that is necessary is to turn lever L' down so as to disengage the T heads of the coupling-bar from their respective hooked drawheads, and then push the rod L to one side, as already described.

If desired, the coupling bar may be constructed as shown in Fig. 6, in which I have shown bar G as having a crosshead J at one end only, and an ordinary link J', at the other end. This form of link is intended for use when a car equipped with my improved coupling is to be used with cars of the ordinary pin-and-link coupling, one of these links being carried with each car provided with my improved coupling.

Having thus described my invention, I claim and desire to secure by Letters Patent of the United States—

The combination, in a car coupling, of the bifurcated drawhead having hooks E F, guide O having depending arms o o converging at their lower ends above the curved ends f f of the drawhead-hooks, coupling bar G having cross-heads J J and central rigid link or staple H i, chain I, sliding rod L having arm K and lever handle L', chain I', hooked standard M, and keeper N; all constructed and combined to operate substantially as and for the purpose shown and set forth.

In testimony that I claim the foregoing as my own I have hereunto affixed my signature in presence of two witnesses.

HORACE L. RENNE.
